UNITED STATES PATENT OFFICE

2,004,323

CINDER CHROME BUILDING UNIT

Arvid Hede, Detroit, Mich., assignor to Cinder Chrome Company, Detroit, Mich., a corporation of Michigan

Application July 29, 1932, Serial No. 626,199

5 Claims. (Cl. 72—36)

My invention relates to a chrome finished building unit adapted for building wall construction.

The object of my invention is to produce a special building unit in the form of either slab or block construction, that has the strength and hardness of rock material, yet is very light in weight.

Another object is to produce a building block unit of special structure and composition, having one or more chrome finished surfaces formed thereon.

A further object is to produce a cinder chrome building unit formed of a combination of two or more materials all united in a solid mass, and provided with ventilating channels therethrough, and said building unit being so constructed as to be adapted for either vertical or horizontal air channel construction.

These several objects are attained in the preferred form by the construction and arrangement of parts more fully hereinafter set forth.

Similar parts on the drawing are marked by similar numerals or letters.

Fig. 1 represents a plan view of the chrome finished surface formed on a rectangular building unit, showing the relative positions of the tapered air channels formed therethrough.

Fig. 2 is an end view of the rectangular building unit showing the arrangement of the air channels as are formed therein, where cores of rectangular cross-section are used.

Fig. 3 is a modified end view of the same unit showing the end arrangement of the air channels where cores of cylindrical cross-section are used.

Fig. 4 is an end view of the unit shown in Fig. 1.

It is known that there are various types and kinds of hollow building blocks and units, all constructed of various grades of building material, but not of the structure and formation herein described and claimed.

Much difficulty has been experienced in producing a satisfactory building unit, comprising the appearance of polished marble and the resisting strength of rock, without adding greatly to the weight of the wall structure.

In accomplishing my invention I use a composition of matter comprising ingredients and materials in the various proportions as is more fully set forth and described in my composition patent application Serial No. 626,201, filed July 29, 1932, all compounded as set forth in my process patent application Serial No. 626,200, filed July 29, 1932, the ingredients and elements and materials therein used being sodium silicate, boracic acid, casein, sal-ammoniac, cement, marble dust or sand, and

mineral coloring ingredients, also a special composition of cinder concrete.

In general, my chrome finished building unit comprises an artificial rock backing formed with parallel fluted air channels therethrough, and provided with one or more faces of the chrome finish structure, all made as a solid mass and as an integral unit, and while I illustrate and describe a simple building slab unit with but one finished face, it is to be understood that any desired size or shape unit having more than one finished wall face may also be made and is within the meaning of this patent.

I will now describe more fully the detailed construction of my cinder chrome building unit, referring to the drawing and the marks thereon.

In producing my building unit the mixtures of materials are made in three or more separate containers.

First, a base mixture is prepared from cement, marble dust or fine sand, and a chosen mineral coloring ingredient using cement as a unit portion for comparison, the preferred mixture and proportions are, 1 part cement, 1½ parts of marble dust or fine sand, and soluble mineral coloring of variable amount depending on the color required, the term "part" meaning proportions by measure, all thoroughly mixed together in a dry pulverized state.

Second, a backing mixture is provided from a mixture of cement, sand and crushed cinders in about the following proportions, 1 part cement, 1½ parts sand, and 1 part crushed cinders, also mixed together in a dry state.

Third, a liquid mixing solution is made from sodium silicate, boracic acid, casein, and sal-ammoniac, and water as is more specifically set forth in my process patent application Serial No. 626,200, filed July 29, 1932, heretofore referred to using about the following proportions, 30 gallons of water, 2½ pounds of sodium silicate, 1½ pounds of boracic acid, 3½ pounds of casein, 4½ ounces of sal-ammoniac, and small portions of this solution are separated in different containers, and each provided with a different mineral coloring ingredient.

Both the base mixture and the backing mixture are made into a plastic composition by combining the liquid mixing solution therewith.

A special mould of the required size and shape for making the preferred type of building unit is provided and formed with a polished bottom surface, such as plate glass or other suitable polished material, said polished mould bottom being painted, spotted or splashed until the en-

tire polished surface is covered, using the various colored solutions from the several small containers, said paint application being referred to as the surface glazing coat 1. On top of the glaz-

5 ing coat 1 is poured the plastic base mixture of cement and marble dust mixed with some mineral color, forming a thin layer of colored marble composition 2. Across this marble layer 2 is placed a series of tapered cores 3, either 10 rectangular or cylindrical in form and positioned parallel with each other, said cores extending the entire width of the mould as indicated in Fig. 1 of the drawing. While the marble layer 2 is in the plastic state, the backing mixture of 15 cement and crushed cinders is poured thereon, completely covering the core members 3, forming a non-porous rock backing 4. Slight tamping may be applied to the backing composition for more securely imbedding the coarse cinder 20 concrete aggregate into the marble layer composition, and the entire mass hardening as an integral unit. The special mixing solution permeating the cinder material and reduces it to a consistency of rock formation.

25 After the block composition has sufficiently dried the cores 3 may be removed from the unit by withdrawing same therefrom from one side of the mould, and the unit seasoned until the required hardness is attained. This building slab 30 may be used in wall construction in the full size slab, or sawed into smaller building blocks as indicated by the dotted lines *a* and *b* of Fig. 1.

If desired the core members 3 may be omitted during construction, leaving the entire backing a 35 homogeneous mass, but the air channels which provide a complete circulation therethrough greatly increase the wall strength as all dampness is readily removed therefrom by either horizontal or vertical ventilation.

40 Also when desired the backing 4 formed of cinder concrete may be omitted, and the finished artificial marble slab or block be cemented to the face of any other backing block or wall such as brick or stone &c, although this is not the 45 purpose of the invention, as such uniting of the marble slab or block will greatly diminish the strength and durability of the product, as the hardening properties of the special mixing solution are omitted.

50 It is apparent that my building unit is subject to various modifications in design, shape, sizes and composition of the plastic materials without departing from the spirit of my invention, and that any design such as column or double wall 55 units having one or all faces finished and glazed

may be made, and I claim as my invention the design as herein illustrated and any other design that is substantially a substitution of parts therein shown.

Having fully described my cinder chrome building unit, what I claim as my invention and desire to secure by Letters Patent is:

5 1. A building unit adapted for wall construction, formed of a plurality of different grades of cement concrete portions assembled in consecutive layers, 10 the outer layer being a fine sand concrete containing sodium silicate, boracic acid, casein and sal-ammoniac and is provided with an outside face glazing, said face glazing comprises a mixture of sodium silicate, boracic acid, casein and sal- 15 ammoniac.

2. A building unit adapted for wall construction, formed of a plurality of layers of different grades of cement concrete portions, each layer containing sodium silicate, boracic acid, casein 20 and sal-ammoniac the outer layer being a fine sand concrete artificial marble composition provided with an outside face glazing, said face glazing comprising a mixture of sodium silicate, 25 boracic acid, casein and sal-ammoniac.

3. A building unit adapted for construction purposes formed of a plurality of layers of different grades of cement concrete portions each layer containing sodium silicate, and boracic acid, said outer layer being a fine sand concrete imitation 30 marble composition provided with the outside face glazing, and the inner layer being a cinder concrete mixture, said face glazing comprising a mixture of sodium silicate and boracic acid.

4. A building unit adapted for construction 35 purposes formed of a plurality of different grades of cement concrete portions assembled in parallel layers each layer containing casein and sal-ammoniac, the outer layer being of a hard fine sand concrete artificial marble composition provided with an outside face glazing, the inner layer 40 containing a cinder aggregate said face glazing comprising a mixture of casein and sal-ammoniac.

5. A building unit adapted for building construction formed of two layers of different grades 45 of cement concrete portions assembled in parallel layers each layer containing sodium silicate, boracic acid, casein and sal-ammoniac, one of said cement layers containing marble dust or sand and a mineral coloring ingredient and provided with an outer face glazing, and the other layer containing a coarse concrete aggregate, said face glazing comprising a mixture of sodium silicate, boracic acid, casein and sal-ammoniac.

55 ARVID HEDE.
